corporation of New Jersey

Application November 28, 1947, Serial No. 788,399

12 Claims. (Cl. 274—23)

1

This invention relates to phonograph reproducer mountings, particularly for the reproduction of phonograph and like records having grooved sound tracks adapted to actuate the reproducer through a stylus or needle.

It is a principal object of the invention to provide an improved pivoted mounting for such a reproducer, particularly advantageous in the playing of records in a horizontal position, which eliminates or greatly reduces the tendency of the needle, in certain positions and under certain conditions, to leave the groove with which it is engaged and slide over the surface of the record to a more stable position. This tendency occurs when the engaged portion of the groove extends and is advanced in a direction at an angle to the longitudinal axis of the reproducer arm, or to the line connecting the needle and vertical pivotal axis of the arm if the arm does not follow such line. Actual jumping from one groove to another is more likely to take place when light needle-point pressures are employed and when the apparatus is subject to shock or vibration, although the tendency to jump grooves is inherent in the relation of the forces acting on the needle.

When the sound groove and the effective longitudinal axis of the pivoted reproducer arm are at an angle to one another, there exists a component of the frictional force or drag of the advancing groove on the needle which has a moment about the vertical pivotal axis of the reproducer arm tending to rotate the arm and move the needle to a new groove, or a new convolution in the case of a continuous spiral groove, where the longitudinal axis of the arm and the engaged groove are substantially parallel. For example, if the recording medium is a film strip in which a number of parallel sound grooves are formed and which lies and is advanced substantially in a horizontal plane at the point of engagement of the reproducer needle therewith, and if the vertical pivot about which the reproducer arm swings is centrally disposed relative to the strip, there is a tendency for the needle when following any but the central grooves to jump out of the engaged groove and slide over the surface of the strip to a more centrally located one. This tendency increases as the length of the reproducer arm is shortened.

In many applications it is highly desirable to use a short reproducer arm, to facilitate compact design. It is also desirable to use fine record grooves so as to obtain as much information as possible from a given area of record surface.

2

Low needle-point pressures are desirable to reduce record and needle wear. All these factors increase the tendency of the needle, when engaging a groove lying at an angle to the effective longitudinal axis of the reproducer arm, to jump to a groove more nearly aligned with said axis.

The present invention makes use of the weight of the pickup arm to provide an outwardly-acting force to at least partially counteract the inwardly-acting force due to contact between needle and groove, thereby decreasing the tendency to jump grooves. This is accomplished by tilting the conventional vertical pivotal axis of the arm. The relation between the angle or tilt of this axis and the factors affecting stability of the needle will be referred to more in detail in the following description of a specific embodiment, with reference to the appended drawings in which:

Fig. 1 is a fractional elevational view of a sound reproducing apparatus including a reproducer mounting in accordance with the invention;

Fig. 2 is a plan view of the record medium of Fig. 1, together with a diagram illustrating certain force relationships involved in the operation of reproducer mountings;

Fig. 3 is a diagrammatic side view of a reproducer mounting, illustrating certain features of the invention;

Fig. 4 is a top view of the reproducer of Fig. 3; and

Figs. 5 and 6 are diagrams illustrating the manner in which the tilt of the axis results in an outward force at the needle.

Fig. 1 illustrates the application of the reproducer mounting of the invention to sound apparatus employing as a record medium an endless loop of film strip 11, having a portion thereof coiled into a roll rotatably supported on rollers 12, mounted in circular array on a panel or supporting member 13. A pair of rotatably reversible guard members 14 in the illustrated position thereof prevent the film roll from slipping off the supporting rollers, and may be positioned to permit mounting the roll thereupon.

Film strip 11 is advanced longitudinally by the engagement of edge perforations 15 thereof with a sprocket 16 driven from motive means, not shown. The axis of the film roll and the axes of rollers 12 are necessarily at a slight angle to the axis of sprocket 16, due to the endless nature of the film strip. In its travel the strip passes over a slightly curved platen 20 and at a portion thereof where the film is substantially horizontal is engaged, in one of sound grooves 21 of the film, by reproducer stylus or needle 22, which is

operatively connected to actuate a reproducer head 23 carried at the front end of reproducer arm 25. The reproducer head converts lateral variations in the sound grooves into an electric wave as is well known.

The reproducer head and its mounting are located within the film roll, as shown, to yield a compact design. The length of arm 25 is hence restricted. In certain designs an effective arm length of the order of 3 inches is the maximum possible. The present invention enables such short arms to be employed while maintaining stable tracking.

Reproducer arm 25, in accordance with the principles of the invention, is pivoted on a movable support member, here shown as bracket 27, about an axis 26 which allows movement of the reproducer head 23 in a direction normal to the plane of the record grooves, that is, in the vertical direction in the embodiment shown. Bracket 27 in turn is pivoted to a fixed support, here shown as bracket 28, about an axis 30 which is inclined at an acute angle to the vertical (angle α in Fig. 3). Axis 26 is advantageously offset from axis 30 in the direction of the reproducer head, as shown, the amount of offset being small compared to the arm length.

When using a strip film record, it is advantageous to locate axis 30 in a vertical plane passing through a central part of the record groove surface, so that the lateral excursions of the reproducer head are approximately equal on each side. Axis 26 is advantageously at right angles to axis 30, and horizontal when the head engages a central groove. As the head moves laterally in either direction, axis 26 moves in an arc about axis 30 and accordingly tilts downwardly in the corresponding direction.

In Fig. 2 there are shown certain of the horizontal forces and components thereof acting on a reproducer arm pivoted about a vertical axis through a point 0 centrally located relative to the film, for different positions and lengths of the arm. A vertical axis through 0 in Fig. 2 may be taken to correspond to the line C—C', in Fig. 3, which illustrates the position axis 30 of the reproducer arm mounting would assume if rotated to the vertical about axis 26. Sound grooves 21 are shown broken away, for clarity of illustration, but will be understood to be continuous in ordinary practice.

Assume that a reproducer arm, represented as to effective length and position by the line 0—A, mounts a needle at point A subjected to a frictional drag f in the direction in which the sound groove advances. When the film and the sound grooves therein advance in the direction of arrow 35, there is no tendency for the needle at point A to slide laterally over the film, since the force f , due to the longitudinal drag of the groove on the needle, lies along the effective longitudinal axis of the arm. However, when an arm of the same length is in the position 0—A', with the needle at A' engaging one of the outer sound grooves 21 of the strip, the force f has a component f_n normal to the arm axis and this component has a moment about 0 tending to slide the needle to the point A. This normal component of the frictional drag decreases as the length of the arm is increased, for example, to a value f_n' if the arm is increased in length to 0—B.

In the diagram the force f , the pull of the needle in the direction in which the groove is advancing, has been assumed constant for sim-

plicity of explanation and the force vector of the resistance to lateral sliding of the needle is not shown. The forces due to lateral movement of the needle produced by the recorded waves in the record grooves have also been omitted, for simplicity.

Considering now the effect of the tilt of the axis, Figs. 5 and 6 will be referred to. Fig. 5 is a force diagram in a horizontal plane with the pickup or reproducer head assumed to be engaging an outer groove of the record. Fig. 6 is a force diagram in a vertical plane through the center of gravity normal to the pickup axis, the point of view being indicated by arrows 6—6 in Fig. 5.

In Fig. 5, 41 is a center line down the record film 11 through the tilted axis 30. The center line through the pickup is denoted 42.

In Fig. 6, center line 43 coincides with axis 30, and appears at an angle due to the projection of the angle of tilt of axis 30 onto the vertical plane 6—6. The weight of the pickup arm, acting at its center of gravity, results in a downward force f_w due to gravity. This force may be resolved into component 44 along the center line 43 and component 45 perpendicular thereto. The latter component may in turn be resolved into a force parallel to f_w and force f_h in the horizontal plane.

Referring again to Fig. 5, force f_h is shown applied at the assumed center of gravity of the pickup arm along center line 42. It is evident that f_h results in a torque tending to swing the arm outward. The resultant force at the needle is shown as f_0 , and is smaller than f_h since it is farther from the pivot point.

It is evident that f_0 is opposite to f_h in Fig. 2, and hence tends to counteract it. Both forces are zero when the needle is in a center groove, and both increase as the needle moves more and more toward the outer grooves. This is advantageous. Actually it is not necessary that force f_0 exactly counterbalance force f_h , so long as the resultant force does not exceed that required to lift the needle out of the groove. In addition to diminishing the tendency to jump grooves, the counteracting force f_0 reduces record wear by reducing the lateral force on the sides of the grooves.

As the pickup moves toward the outer grooves the axis 26 (Fig. 3) does not remain exactly horizontal, but tilts slightly. This tilt may also contribute somewhat to the outward force at the needle.

The effect of the tilt may also be considered from the point of view that since axis 26 moves in an arc of a circle around axis 30, it moves downward on either side of its central position, and thus the rear end of the pickup arm 25 moves downward. Hence, when the needle engages a non-central groove, work must be done on the arm to move it back to a central position. Force f_h is required to do this work, in addition to the work required to lift the needle out of the groove, before the needle can jump a groove.

The above theory, while believed helpful in understanding the effect of tilting the axis, is not insisted upon and is subject to further elaboration.

The optimum angle of tilt is subject to variation depending on several factors, particularly the length and weight of the arm, needle pressure, speed of travel of the record surface, and coefficient of friction of the needle therewith. It has been found possible to calculate approximately

the performance of the arm for given parameters, but in general the difficulty of determining the essential parameters and making the calculation renders the direct determination of the optimum tilt angle far simpler. This may easily be ascertained by constructing the arm of desired length and needle pressure, and placing the needle on an ungrooved record surface traveling at the desired speed. The vertical axis may then be tilted until there is little or no tendency for the needle to move from outer to central portions of the record surface.

As an example for illustrative purposes only, for one model of the invention which operated satisfactorily the following data applied:

Needle pressure	24 grams.
Tilt angle (from vertical)	35°.
Distance from axis 30 to axis 26	15 $\frac{1}{2}$ grams.
Length from axis 26 to needle	3 $\frac{1}{2}$ grams.
Needle angle (from horizontal film)	70°.
35 mm. film speed	60 ft./min.

As examples of variations in tilt angle with other parameters, the following observations have been made. As the film speed is increased, with other parameters unchanged, larger tilt angles are in general required to prevent or minimize lateral movement of the needle on an ungrooved film. Such increased film speed increases the force due to needle friction f_n and hence requires a somewhat greater force f_b to counteract it.

For a light weight pickup arm 7 inches long, as the reproducer head was moved from a distance of 2.75 to 7 inches from the tilted axis, and needle pressure maintained constant at 35 grams by gram weights over the needle point, the optimum tilt angle increased somewhat. However, for arm lengths above about 5 inches, when used with a 35 mm. film, the force f_n was sufficiently small so that a vertical pivot sufficed without danger of jumping grooves in normal play. For arms shorter than about 5 inches the tilt angle assisted materially in improving tracking stability. In another case where the arm length was increased as the reproducer head was moved from 2.75 to 7 inches, thereby increasing the weight of the arm itself, while the needle pressure was maintained constant at 35 grams by gram weights over the needle point, the optimum tilt angle decreased slightly, averaging about 40 degrees.

It has also been found that if the needle point pressure is increased by added force applied over the needle, as by weights, etc., without changing other factors, the optimum tilt angle is increased somewhat, presumably due to the increase in force f_n which requires additional tilt to increase the counteracting force f_b .

It is believed that the above discussion of the effect of certain parameters on the optimum tilt angle will assist in the ready practice of the invention. Also, as previously pointed out, it is usually easier in practice to simply vary the tilt angle in a given case to determine the optimum, keeping in mind that adequate tracking is often obtained even though the tilt angle is not optimum due to the factor of safety introduced by the force required to lift the needle out of the groove. In general, it has been found that backward tilt angles between 20° and 45° degrees suffice to give proper tracking. The optimum angle within this range may be selected for the particular conditions applying, as above discussed. Angles greater than 45° have been employed with

success, but appear to be unnecessary in most cases.

A preferred embodiment of the invention has been described above for use with a film record. It will be understood that the specific details given may be departed from to fit the conditions of a given application, within the scope of the invention. It will also be understood that the invention is applicable to disk records as well as the film records specifically described.

I claim:

1. A phonograph reproducer mounting for reproducing sound from record grooves which are substantially horizontal at the point of reproduction comprising a fixed support, a movable support member pivoted to said fixed support about an axis inclined backwards with respect to the reproducer mounting in playing position at a substantial acute angle with the normal to the plane of the record grooves at the point of reproduction, and a generally horizontal arm having a free front end bearing a reproducer head and pivoted near the rear end thereof to said movable support member about an axis allowing movement of said head in the direction normal to said plane of the record grooves.
2. A phonograph reproducer mounting for reproducing sound from record grooves which are substantially horizontal at the point of reproduction comprising a fixed support, a movable support member pivoted to said fixed support about an axis inclined backwards with respect to the reproducer mounting in playing position at a substantial acute angle with the normal to the plane of the record grooves at the point of reproduction, and a generally horizontal arm having a free front end bearing a reproducer head and pivoted near the rear end thereof to said movable support member about a lateral axis substantially at right angles to said inclined axis.
3. A phonograph reproducer mounting for reproducing sound from record grooves which are substantially horizontal at the point of reproduction comprising a fixed support, a movable support member pivoted to said fixed support about an axis inclined backwards with respect to the reproducer mounting in playing position at a substantial acute angle with the normal to the plane of the record grooves at the point of reproduction, and a generally horizontal arm having a free front end bearing a reproducer head and pivoted near the rear end thereof to said movable support member about a lateral axis substantially at right angles to said inclined axis and offset with respect thereto by a distance small compared to the length of said arm.
4. A phonograph reproducer mounting comprising a generally horizontal arm having a free front end bearing a reproducer head for engaging a substantially horizontal record surface, a movable support member pivoting the rear end of said arm about a lateral axis, and a fixed support pivoting said movable support member about an axis inclined backwards with respect to the reproducer mounting in playing position at a substantial acute angle to the vertical.
5. A phonograph reproducer mounting comprising a fixed support, a movable support member pivoted to said fixed support about an axis inclined backwards with respect to the reproducer mounting in playing position at a substantial acute angle to the vertical, and a generally horizontal arm having a free front end bearing a reproducer head and pivoted toward the rear end thereof to said movable support member about a

lateral axis allowing movement of said head in a vertical direction, said arm being movable through a substantial horizontal angle to permit said reproducer head to traverse a band of record grooves.

6. A phonograph reproducer mounting for reproducing sound from a band of record grooves which are substantially horizontal at the point of reproduction which comprises a fixed support, a movable support member pivoted to said fixed support about an axis inclined backwards with respect to the reproducer mounting in playing position at a substantial acute angle to the vertical, and a generally horizontal arm having a free front end bearing a reproducer head and pivoted toward the rear end thereof to said movable support about a lateral axis substantially at right angles to said inclined axis, said arm being movable through a substantial horizontal angle to permit said reproducer head to traverse a band of record grooves.

7. A phonograph reproducer mounting comprising a fixed support, a movable support member pivoted to said fixed support about an axis inclined backwards with respect to the reproducer mounting in playing position at a substantial acute angle to the vertical, and a generally horizontal arm having a free front end bearing a reproducer head and pivoted toward the rear end thereof to said movable support member about a lateral axis substantially at right angles to said inclined axis and offset with respect thereto by an amount small compared to the length of said arm, said arm being movable through a substantial horizontal angle to permit said reproducer head to traverse a band of record grooves.

8. A phonograph reproducer mounting comprising a fixed support, a movable support member pivoted to said fixed support about an axis inclined backwards with respect to the reproducer mounting in playing position at an acute angle to the vertical greater than about 20 degrees, and a generally horizontal arm having a free front end bearing a reproducer head and pivoted at the rear end thereof to said movable support member about a lateral axis substantially at right angles to said inclined axis and offset with respect thereto by an amount small compared to the length of said arm, said arm being movable through a substantial horizontal angle to permit said reproducer head to traverse a band of record grooves.

9. A phonograph reproducer mounting for reproducing sound from a band of record grooves which are substantially horizontal at the point of reproduction which comprises a fixed support, a movable support member pivoted to said fixed support about an axis inclined backwards with respect to the reproducer mounting at a substantial acute angle to the vertical in a vertical plane passing through a central part of said band of grooves, and a generally horizontal arm having a free front end bearing a reproducer head and pivoted at the rear end thereof to said movable support about a lateral axis substantially at right angles to said inclined axis, said arm being movable through a substantial horizontal angle to permit said reproducer head to traverse said band, said lateral axis being horizontal when the reproducer head is in the central part of said band and tilting as the head engages outer parts of said band.

10. A phonograph reproducer mounting for reproducing sound from a band of record grooves which are substantially horizontal at the point

of reproduction which comprises a fixed support, a movable support member pivoted to said fixed support about an axis inclined backwards with respect to the reproducer mounting at a substantial acute angle to the vertical in a vertical plane passing through a central part of said band of grooves, said acute angle being greater than about 20 degrees, and a generally horizontal arm having a free front end bearing a reproducer head and pivoted at the rear end thereof to said movable support about a lateral axis substantially at right angles to said inclined axis and horizontal when the reproducer engages a central part of said band, said arm being movable through a substantial horizontal angle to permit said reproducer head to traverse said band, whereby the weight of the arm produces an outwardly-acting force as the reproducer head moves laterally from said central part to at least partially counteract the inwardly-acting force due to groove contact.

11. A phonograph reproducer mounting for reproducing sounds from a band of record grooves which are substantially horizontal at the point of reproduction which comprises a fixed support, a movable support member pivoted to said fixed support about an axis inclined backwards with respect to the reproducer mounting at an acute angle to the vertical in a vertical plane passing through a central part of said band of grooves at said point of reproduction, said acute angle being greater than about 20 degrees, and a relatively short generally horizontal arm having a free front end bearing a reproducer head and pivoted at the rear end thereof to said movable support about a lateral axis substantially at right angles to said inclined axis and horizontal when the reproducer engages a central part of said band, said arm being movable through a substantial horizontal angle to permit said reproducer head to traverse said band, the length of said arm being less than about 5 inches from the lateral axis to said point of reproduction and the lateral axis being offset from the inclined axis toward the reproducer head by a distance small compared to the length of the arm, whereby the weight of the arm produces an outwardly-acting force as the reproducer head moves laterally from said central part to at least partially counteract the inwardly-acting force due to groove contact.

12. A phonograph reproducer mounting for reproducing sound from record grooves which are substantially horizontal at the point of reproduction comprising a fixed support, a movable support member pivoted to said fixed support about an axis inclined backwards with respect to the reproducer mounting in playing position at a substantial acute angle to the vertical, and a generally horizontal arm having a free front end bearing a reproducer head and pivoted near the rear end thereof to said movable support member about an axis allowing movement of said head in the direction normal to the plane of the record grooves at the point of reproduction.
